UNITED STATES PATENT OFFICE.

ARTHUR E. GIBBS, OF WAYNE, PENNSYLVANIA.

METHOD FOR THE MANUFACTURE OF CHLORATES AND PERCHLORATES OF ALKALI METALS.

1,173,346.

Specification of Letters Patent. Patented Feb. 29, 1916.

Application filed May 5, 1915. Serial No. 25,971.

To all whom it may concern:

Be it known that I, ARTHUR E. GIBBS, a subject of the King of Great Britain, and a resident of Wayne, in the county of Wayne and State of Pennsylvania, have invented a new and useful Improvement in the Method for the Manufacture of Chlorates and Perchlorates of Alkali Metals, of which the following is a full, clear, and exact description, reference being had to the accompanying drawing, forming part of this specification, in which the figure is a diagrammatic view of one form of apparatus which may be employed for carrying out my invention.

Chlorates have heretofore been chiefly manufactured by one of two methods, viz: (1) by passing an excess of chlorin through milk of lime and separating the produced chlorate; or (2) by electrolyzing a chlorid in a cell without a diaphragm and separating the chlorate thus produced.

My present invention is designed to provide a simple and highly efficient method of producing chlorates and perchlorates which, to some extent, combines features of both these methods.

The electrolytic part of my present method takes place in a cell such as is used for the production of alkali and chlorin. The chlorin produced is removed from the anode compartment before combination with alkali takes place. Some or all of the chlorate and chlorid formed from this combination is returned to the anode compartment of the cell and is allowed to pass through to the cathode compartment when it again becomes strongly alkaline and is ready to absorb more chlorin, thereby increasing its chlorate content. The chlorate is separated as hereinafter described.

In the accompanying drawing I have illustrated, diagrammatically, one apparatus for carrying out my invention; namely an electrolytic cell 2 such as is used for the production of caustic alkali and chlorin and which may be of the mercury, diaphragm or other type. I find, however, that the type of cell described and claimed in my Patent No. 874,064 dated December 17, 1907, is particularly efficient for this work by reason of the large space for anode liquor as compared with the volume occupied by the anodes. Furthermore, the diaphragm used in this cell prevents contamination of the chlorate with carbonaceous matter resulting from

breaking down or disintegration of the anodes. I have accordingly illustrated a cell of this type at 2 in the accompanying drawing. 3 designates the anodes, 4 the perforated sheet metal cathode and 5 the diaphragm. 6 is the elevated cup connected with the interior of the anode chamber by the feed pipe 7.

The outlet pipe 8 from the cathode compartment of the cell leads through a suitable pump 9 into a tank 10, provided with a suitable agitator 11. The tank 10 has an overflow connection at 12 into a settling tank 13. The tank 10 is also preferably provided with a bottom draw-off 14, and the tank 13 is shown as having a similar bottom draw-off 15. The upper portion of the settling tank is connected by a pipe 16 with the upper portion of an absorption tower 17. 18 is an off-take connection from said tower leading to an exhaust fan 19. The tower 17 discharges at the bottom into a solution tank 20 which is connected by a pipe 20^a with another solution tank 20^b having a siphon connection 21 with the feed cup 6. 22 is an overflow pipe for the cup 6 leading into a tank 23 which is connected back to the tank 20^b through a pump 24 and pipe 25. 26 is a pipe leading from the top of the anode chamber of the cell 2 into the lower portion of the tower 17.

When sodium chlorate is the product desired, the method may be started and carried out as follows: A solution of sodium chlorid is supplied to the feed cup 6 from whence it passes into the anode compartment of the cell 2 and is electrolyzed. The caustic or cathode liquor is drawn from the cathode compartment of the cell by means of the pump 9 and flows into the tank 10, from which it overflows into the tank 13, and thence into the tower 17. In passing through this tower it meets an ascending current of chlorin gas delivered from the pipe 26 from the anode compartment. Hypochlorite of soda is formed and this is converted into chlorate by the excess of chlorin which exists near the bottom of the tower. If the conversion to chlorate is not otherwise complete, artificial heat may be supplied in any suitable manner. In the event of any unconverted hypochlorite passing into the tank 20^b and thence to the cell 2, it is immediately oxidized in the anode compartment of the cell. The overflow from the feed cup

6 falls into the tank 23 and is returned by the pump 24 to the tank 20^b. During the operation, sodium chlorid is supplied to the tank 10 to keep the solution saturated to as high a degree as is practicable with that salt. After the liquors have circulated through the system a number of times, the chlorate gradually increases in amount and the liquor is then removed and concentrated for the recovery of the chlorate. The salt which separates out can be returned to the system.

The alkaline liquor coming from the cathode compartment of the cell, contains, in solution, sodium chlorid, sodium chlorate, caustic soda, and some carbonate of soda. The electrolyte in its passage through the cell has been depleted of some of its sodium chlorid and this loss is made up by the addition of more sodium chlorid to the tank 10, as before described. A convenient way of getting this sodium chlorid into the solution is by means of the agitator 11. The grade of salt usually employed for this work does not dissolve to a clear solution. It also usually contains some calcium, and magnesium salts. This is precipitated in the tank 10 by the caustic and carbonated alkali. Some of this sediment or precipitate settles out at the bottom of the tank 10, and the remainder passes on to tank 13, in which it settles. These precipitates are drawn off at 14 and 15.

The precipitation of the lime or magnesia salts, which are usually present in the chlorid salts, added to the tank 10, is at the expense of some of the caustic or carbonated alkali present in this tank. The result of this, together with the removal of the chlorate from the solution at the bottom of the tanks 10 and 13 is a deficiency of the alkali with respect to the chlorin produced in the cell, so that there is a sufficient excess of chlorin present in the absorption tower 17, to effect the conversion of hypochlorites to chlorates in said tower. If a pure chlorid should be added in the tank 10, the excess of chlorin would be maintained by withdrawing some alkaline liquor at either 14 or 15.

Potassium chlorate can be conveniently made by using a potassium chlorid, electrolyte, or a mixture of potassium and sodium chlorids in solution, or by adding potassium chlorid to the sodium chlorid electrolyte above described. Double decomposition between the sodium chlorate and potassium chlorid takes place and the less soluble potassium chlorate separates out.

The chlorate of potash may be removed either at 14 or 15. It is in the form of a sludge, and may then be purified in any usual way, as by placing it in a centrifuge to separate the caustic liquor from the chlorate and from the insoluble mud precipitated from the commercial chlorid which is

added at this point. The sludge can then be purified by re-dissolving, settling and crystallizing or concentrating by well known methods. While drawing the sludge off at 14, connections may be made so that the liquid from pump 9 will go direct to tank 13. Similarly, when the sludge is drawn off at 15, the liquid may be passed directly from the tank 13 to the tower 17 by any suitable connection. The operations for either chlorate of soda or chlorate of potassium are generally similar, except that in the case of the former, it being very soluble, does not crystallize in the vessels 10 or 13, but must be drawn off and concentrated. The sodium chlorid which separates out first can be returned to the system. By circulating the liquor through the cell a number of times, the proportion of chlorate to chlorid is greatly increased, and the solution going to the concentrators can thus be made to contain more chlorate than chlorid. As the reaction between caustic and chlorin to produce chlorate is such that five molecules of chlorid are produced to one molecule of chlorate, this feature is of great importance. The necessity of handling a large amount of chlorid for a small production of chlorate has caused the commercial abandonment of many other methods which have been tried.

It is obvious that many changes can be made in the apparatus used and in the details of the method described, without departing from the spirit and scope of my invention, as defined in the appended claims, thus, instead of one absorption tower several may be employed. Instead of removing the chlorate from the alkaline liquor, I may remove it from the liquor at any other desirable point in the system. The alkali formed in the cathode compartment is not necessarily used to absorb chlorin, since carbonate of soda or other cheaper alkali may be used for this purpose, and the more valuable caustic alkali can be separated from the chlorate and chlorid, and sold or used as such. Similarly, if it is desirable to use the strong chlorin produced in the cell for purposes other than chlorate such as for making liquid chlorin, I can replace the amount so used with chlorin from another source or produced by chemical means. But whatever the source of the alkali and chlorin, I prefer to supply these to the system outside of the cell in such proportions that the chlorin is in excess, the chlorate and chlorid thus produced being returned to the electrolytic cell. If a mercury or gravity type of cell is used, I prefer to filter or thoroughly settle the liquors containing the chlorate, in order to avoid the danger caused by the presence of carbonaceous matter in the chlorate. If a cell is used with a mercury cathode, some or all of the solution contain-

ing chlorate and chlorid is allowed to pass to the cathode compartment, preferably from the anode compartment, where it is decomposed by the sodium in the mercury, 5 forming caustic soda and hydrogen, the chlorate being substantially unaltered. By continuing the electrolysis sufficiently, or by using a chlorate for the electrolyte and lowering the temperature, perchlorates can be 10 made in the cell without using an outside absorption system.

Some of the advantages resulting from my invention are as follows: The operation can be carried out at a temperature considerably 15 in excess of 40° centigrade without causing undue corrosion of the electrodes. As the conductivity of wet electrolytes increases with the increase of temperature, the cell can be run at a lower voltage at the 20 higher temperature. The addition to the electrolyte of chromic acid or its salts can be dispensed with. Power efficiency exceeding 52% of the theoretical efficiency can be obtained, assuming the decomposition voltage 25 of sodium chlorid to be 2.02 volts. When carbon or graphite anodes are used in connection with a diaphragm cell, contamination of the chlorate with carbonaceous matter is prevented. The grinding of chlorate 30 is attended with considerable danger; and this danger is greatly increased if carbonaceous matter is present. The diaphragm being an excellent filter removes from the system all of the carbon or graphite 35 which disintegrates from the electrodes.

The removal of the chlorate from the electrolyte is accomplished without disengaging or losing chlorin and without discomfort to the workmen. This is because the chlorate 40 is removed from the system at a point between the electrolyzing apparatus and the absorption chamber where there is no chlorin present and the strong alkaline liquor is free from odor or corrosive action on iron.

45 The solution containing chlorate being strongly alkaline and substantially free from hypochlorite, entails less expense for apparatus and the problem of handling, cooling, heating, and concentrating these 50 liquors is simplified to a considerable extent.

The use of an alkali chlorin cell makes negligible the loss of efficiency caused by the reducing action of the hydrogen, the chlorate subjected to the action of nascent hydrogen being always in the cathode compartment and strongly alkaline. Chlorate 55 is not reduced to any appreciable extent by nascent hydrogen if the solution is alkaline.

60 The loss of efficiency which occurs in chlorate cells with secondary electrodes, due to the jumping of the current around some of the electrodes, is avoided in my improved method.

65 I claim:

1. The herein described method of mak-

ing a chlorate, which consists in electrolyzing a chlorid solution to produce chlorin and an alkali, uniting the chlorin and the alkali outside of the anode and cathode compartments of the electrolyzing apparatus, 70 and diminishing the quantity of the produced alkali passing to the combining chamber relatively to the amount of chlorin, to thereby maintain an excess of chlorin in the combining chamber. 75

2. The herein described method of making a chlorate, which consists in electrolyzing a chlorid solution to produce chlorin and an alkali, uniting the chlorin and the alkali outside of the anode and cathode compartments of the electrolyzing apparatus, 80 maintaining an excess of chlorin in the combining chamber, and returning the chlorate liquor resulting from the combination to the electrolyzing apparatus and repeating 85 the described operations.

3. The herein described method of making a chlorate, which consists in electrolyzing a chlorid solution to produce chlorin and an alkali, uniting the chlorin and the 90 alkali outside of the anode and cathode compartments of the electrolyzing apparatus, maintaining an excess of chlorin in the combining chamber, and returning the chlorate liquor resulting from the combination to the 95 anode compartment of the electrolyzing apparatus.

4. The herein described method of making a chlorate salt, which consists in electrolyzing a chlorid solution to produce chlorin and an alkali, discharging the alkali solution from the cathode compartment of the electrolyzing apparatus and the chlorin from the anode compartment of the electrolyzing apparatus, adding fresh chlorid to the alkali solution, and then bringing the solution into contact with the chlorin to produce a chlorate liquor. 100 105

5. The herein described method of making a chlorate salt, which consists in electrolyzing a chlorid solution to produce chlorin and an alkali, discharging the alkali solution from the cathode compartment of the electrolyzing apparatus and the chlorin from the anode compartment of the electrolyzing 110 apparatus, adding fresh chlorid to the alkali solution, then bringing the solution into contact with the chlorin to produce a chlorate liquor, returning said liquor to the anode compartment of the electrolyzing apparatus, 115 and repeating the cycle of operations, and removing chlorate from the alkaline liquor at a point in the system intermediate the electrolyzing apparatus and the absorption chamber where the chlorin and alkali are 120 combined.

6. The herein described method of making chlorate salt, which consists in electrolyzing a chlorid solution in a diaphragm cell having carbon or graphite electrodes, to pro- 130

duce chlorin and an alkali liquor, withdrawing the chlorin from the anode compartment of the electrolyzing apparatus, withdrawing the alkaline liquor from the cathode compartment of the electrolyzing apparatus, uniting the chlorin and the alkaline liquor outside of both said compartments and circulating the chlorate liquor repeatedly through the cell to increase the proportion 5 of the chlorate contained therein, and maintaining an excess of chlorin in the combining chamber.

7. The herein described method of making a chlorate salt, which consists in electrolyzing a solution containing both a chlorid and a chlorate, the major portion of the chlorate passing to the cathode compartment of the electrolyzing apparatus without change, and the chlorid being electrolyzed therein to 10 form chlorin and a caustic alkali, conducting the chlorin to an absorption chamber, adding fresh chlorid to the alkaline solution discharged from the cathode compartment of the electrolyzing apparatus, and then bringing the alkaline liquor into contact with the chlorin, and removing chlorate from the system at a point between the electrolyzing apparatus and the absorption chamber.

8. The method of making a chlorate salt, which consists in electrolyzing a chlorid solution, bringing the alkaline liquor from the cathode compartment of the electrolyzing apparatus into contact with an excess of chlorin, outside of the anode and cathode compartments of said apparatus, returning the chlorate containing solution to the said apparatus, and repeating the cycle of opera-

tions with a fresh supply of chlorid mixed with the solution, and removing chlorate from the alkali liquor at a point between the 40 electrolyzing apparatus and the absorption chamber.

9. The method of making a perchlorate salt, which consists in electrolyzing a chlorid solution, bringing the alkaline liquor from the cathode compartment of the electrolyzing apparatus into contact with an excess of chlorin gas outside of the anode and cathode compartments of said apparatus, returning the resulting chlorate containing solution to 45 the electrolyzing apparatus, and repeating the cycle of operations until a perchlorate is produced in the alkaline liquor.

10. The method of making a perchlorate salt, which consists in electrolyzing a chlorid 50 solution, bringing the alkaline liquor from the cathode compartment of the electrolyzing apparatus into contact with an excess of chlorin gas outside of the anode and cathode compartments of said apparatus, returning 55 the resulting chlorate containing solution to the electrolyzing apparatus, repeating the cycle of operations until a perchlorate is produced in the alkaline liquor, and removing the perchlorate from the system at a point 60 intermediate the electrolyzing apparatus and absorption chamber.

In testimony whereof, I have hereunto set my hand.

ARTHUR E. GIBBS.
